TRIMMER-SPREADER ROAD CONSTRUCTION MACHINE OR THE LIKE

Thomas L. Steele, Oklahoma City, and Warren W. Grist,
Yukon, Okla., assignors to CMI Corporation, Okla-
homa City, Okla.

Filed July 12, 1971, Ser. No. 161,390

Term of patent 14 years

Int. Cl. D12—09

U.S. Cl. D14—3

— I —. 1

— I —. 2

FIG. 2

FIG. 3

FIG. 1 is a left side elevation view of a trimmer-spreader road construction machine embodying our design;

FIG. 2 is a top view thereof, it being understood that the surface texture which is fragmentarily shown continues throughout the designated area;

FIG. 3 is a right side elevation view thereof;

FIG. 4 is a bottom view thereof;

FIG. 5 is a front elevation view thereof; and

FIG. 6 is a rear elevation view of the trimmer-spreader road construction machine.

I claim:

The ornamental design for a trimmer-spreader road construction machine or the like, as shown and described.
